The ornamental design for a spooled wire dispenser, as shown and described.

DESCRIPTION

FIG. 1 is a perspective view of a spooled wire dispenser showing our new design;

FIG. 2 is a front elevational view thereof;

FIG. 3 is a left side elevational view thereof, the right side elevation being a mirror image thereof;

FIG. 4 is a rear elevational view thereof;

FIG. 5 is a top plan view thereof; and,

FIG. 6 is a bottom plan view thereof.

FIG.1

FIG.2
